UNITED STATES PATENT OFFICE

DAVID A. LITTLE, OF PHILADELPHIA, PENNSYLVANIA

GRATE

Application filed January 14, 1931. Serial No. 508,737.

My invention relates to grates for stoves or furnaces in which small anthracite coal may be used as fuel.

The main purpose of my invention is to provide a grate for burning fine fuel with a supplemental air-supplying section which can be used to adjustably break up the fuel bed and feed air within the body of the fuel bed at the points where the bed has been disturbed.

A further purpose is to provide a grate with two sets of bars movable under different laws of movement and each set having independent lever control mechanism.

A further purpose is to provide a grate bar construction for burning small anthracite coal which comprises two sets of bars, one set being pivoted to oscillate and the other set adapted to vertical movement to adjust the supply of air and to release it within the body of the fire bed.

A further purpose is to provide a grate that is easy to manufacture and to install and which at the same time well meets the needs of service.

A further purpose is to provide special air-admitting grate means which is useful also to remove ashes at the point of using.

Further purposes will appear in the specification and in the claims.

I have elected to show one form only of the many different forms of my invention, selecting a form that is practical and efficient in operation and which well illustrates the principles involved.

Figure 1 is a vertical section of a furnace taken on a line which would correspond with line A—A of Figure 2 and showing a grate 40 of that general character in place in a furnace.

Figure 2 is a top plan view of one species of my improved grate detached from the furnace.

Figure 3 is a side elevation of the grate seen in Figure 2.

Figure 4 is a sectional elevation taken on the line 4—4 of Figure 2.

Figure 5 is a sectional elevation of one of the air control grate bars corresponding to

the structure seen in Figure 4 but with the surrounding parts removed.

Figure 6 is a sectional plan view taken on the line 6—6 of Figure 5. Figure 6a is an enlarged fragmentary sectional plan view taken on the line 6a—6a of Figure 4.

Figure 7 is a section taken on the line 7—7 of Figure 5.

Figure 8 is an end view of the bar shown in Figure 5.

Like numerals refer to like parts throughout the drawings.

Describing in illustration but not in limitation and referring to the drawings:—

My grate is particularly designed for the purpose of burning small anthracite coal such as buckwheat, rice or the like.

The grates which have been produced heretofore for the above purpose have generally required artificial draft and so frankly have been admitted to be inoperative without this draft that this requirement is accepted in the art as inevitable. This condition is due to the absence of proper facilities for displacing the ashes and for adjustably releasing air within the body of the bed.

In the structure illustrated in Figure 1 I place my grate 10 in a furnace 11, by inserting pins 12 through downwardly depending lugs 13 of the furnace into apertures 14 in the side bars 15 of the grate 10.

The method of installation must, of course, be varied according to the type or make of the furnace and the design of its base portion; and my illustration must, therefore, be considered as largely diagrammatic.

My grate 10 comprises side bars 15 and end bars 16, the side bars 15 being recessed at 17 to receive the ends 18 of the end bars 16. I also provide the ends 18 with tapered pins 19 which project downwardly through openings 20 in the side bars 15 and fastening pins 21 are inserted through the tapered pins 19 to hold the frame together securely.

In the form shown three raker bars 22, 23 and 24 are pivoted at 25 in the side frames 15. These raker arms also have each a downwardly projecting ear 26 to which is secured a common operating lever 27.

The lever 27, notched at 28 at its outer end, presents three upwardly extending arms 29, 30 and 31 to make pivotal connection at 32 with downwardly projecting ears 5 26 of the raker bars 22, 23 and 24.

Adjacent the raker bars, and most desirably between them and close enough to interfit with them, I place two vertically movable grate bars 33 and 34 containing a 10 series of holes 50 which when raised or lowered will allow more or less air to circulate through the fire bed in the furnace.

These bars 33 and 34 are joined by a bridge or tie bar 35 at their lower ends. At 15 the center of the tie bar 35 a pivoted connection 36 is made with a link 37 which at its outer end 38 is secured to one end 39 of the bell crank lever 40.

The bell crank lever 40 is pivoted at 20 41 to a fixed downwardly projecting lug 42, preferably integral with the end bar 16. The other end 43 of the bell crank lever is pivoted to and is operated by a movable rod 44 notched at 45 at its outer end so that 25 the rod 44 will retain the bars 33 and 34 at any desired height adjustments by reason of engagement of the notches in suitable projections 46 in the base of the furnace.

It will be clearly seen that by moving the 30 operating lever 27 back and forth the raker bars will oscillate and clear the ashes from the bottom of the fire bed, the ashes passing through the spaces 47 when the bars are tilted in an angular position.

35 The vertically movable bars 33 and 34 tend to break up the clinkers in the bed but find their greatest utility in independently, and in conjunction with disturbing the bed, admitting additional air in the disturbed bed 40 area. They are hollow as shown at 48 and air enters at the bottom 49, passing from the hollowed portion 48, through apertures 50. These apertures may be in row formation and it will be obvious that by raising 45 the bar higher into the fire bed as indicated by dot-and-dash lines in Figure 1, air will be released within the bed at points much nearer the surface of the bed than are the rocker bars. The increased air supply thus secured causes the fire to burn more rapidly.

In a general way it is intended in Figure 1 to indicate that the sides of the vertically movable bars and the sides of the rocker bars interfit as by having ribs, fins, teeth 55 or projections on one set extend laterally into the body of the other or fit between ribs, fins, teeth or projections of the other. This is considered by me not only to be generally desirable but assists in keeping the 60 apertures 50 free from clogging.

In Figure 2 I have shown one species among a number which would show up in cross-section as seen in Figure 1; it being my intention not to restrict myself to one 65 type of grate that would agree with Figure

1, nor indeed to forms of which Figure 1 would be true, as I consider that my invention is much broader than this and is applicable to a great variety of forms.

In Figure 2 not only the side bars 15 but also the rocker and vertically movable bars are serrated or otherwise formed on the sides so as to have projections or ribs from one 70 interfit with projections or ribs on the body of the next adjacent structure.

In the illustration the side bars 15 have long and short lugs, projections or fins 51 and 52, opposite alternating long and short lugs, projections or fins 53 and 54 are so placed that the long projections from the rocker bars lie opposite the short projections from the fixed end bars and the short projections from the rocker bars lie opposite the 80 long projections from the fixed end bars.

Opposite sides of the rocker bars as shown 85 correspond. The bar 23 is shown as of the same character as regards its lateral projections as the bars 22 and 24 and the vertically movable bars on opposite sides of bar 23 are provided with lugs, projections or ribs 55 which fit between the long projections 53.

The end bars 16 are provided further with 90 pairs of lugs 59—59 which form guides 60 for the reception of ribs 61 formed on a downwardly extending projection 62 of the vertically movable bars 33 and 34. The ribs 61 riding within the grooves 60 keep the bars 33 and 34 in correct alignment during their 95 vertical movement.

Though the broader aspects of my invention do not contemplate that any such special arrangement of adjoining faces (with or without projections) of the bars shall be used the form shown is quite desirable in that it not only provides for suitable air 100 space during normal furnace operation but presents effective staggered spacings 56 and 57 with suitable bed supporting projections breaking up the line of support to advantage.

In addition to the function already outlined of breaking up the bed and giving additional air within the disturbed area, downward movement of the vertically movable bars may be used to additionally clear out the ash along the faces of the vertically movable bars so as to free the openings 50. The side surfaces 58 of the vertically movable bars will ordinarily be rough enough to rake the ash with them on their downward strokes, but can of course readily be roughened for this purpose if desired.

It will be obvious that the vertically movable bars may be used to advantage in other types of grate and with other types of grate bars, fixed or movable and with a great variety of side surfaces, plain or interfitting.

In view of my invention and disclosure 130 variations and modifications to meet indi-

vidual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:—

1. A grate for burning fine coal consisting of a plurality of spaced rocking grate units, a grate frame for supporting the said units, a lever mechanism for rocking the units, crowned, hollow, laterally-apertured, vertically movable grate units, guides therefore, interfitting projections upon the rocking and vertically movable units and a lever mechanism for imparting vertical movement to the crowned units.

2. A coal burning grate comprising oscillating grate units and vertically movable grate units, the latter composed of hollow rectangular bodies having a series of openings in the side walls arranged in rows one above the other, a grate frame for supporting the said units, guides integral with the frame and adapted to guide the vertically movable grate units, and lever mechanism for raising them above and lowering them below the oscillating grate units.

3. A coal burning grate comprising oscillating grate units and vertically movable grate units, lateral projections on each grate unit and adapted to pass between one another, a grate frame for supporting the said units, vertical guides integral with the frame and adapted to guide the vertically movable units and bearings integral with the grade body adapted to receive the oscillating units.

4. A coal burning grate comprising oscillating grate units, a grate frame for supporting said units, and vertically movable grate units, lateral projections on each of said units interfitting one with the other, manual control for the movement of the oscillating units and separate manual control for the movement of the vertically movable grate units.

5. A coal burning grate comprising oscillating grate units and vertically movable grate units, the latter composed of hollow rectangular bodies having a series of openings in the side walls arranged in rows one above the other, a grate frame for supporting said units, guides integral with the frame and adapted to guide the vertically movable grate units, and lever mechanism for raising them above and lowering them below the oscillating grate units and means for maintaining the vertically movable units in a plurality of relative positions with respect to the oscillating grate units.

6. A coal burning grate comprising oscillating grate units and vertically movable

grate units, the latter composed of hollow rectangular bodies having a series of conical openings in the side walls arranged in rows one above the other, a grate frame for supporting said units, guides integral with the body and adapted to guide the vertical movable grate units, and lever mechanism for raising them above and lowering them below the oscillating grate units.

7. A coal burning grate comprising oscillating grate units and vertically movable grate units, lateral projections on each of said grate units adapted to pass between one another, a grate frame for supporting said units, lateral extensions thereon and adapted to form part of the grate surface, vertical guide lugs thereon adapted to form guideways for the vertically movable grate units and depending lugs thereon adapted to form fulcrum points for the oscillating grate units.

8. A coal burning grate comprising oscillating grate units and vertically movable grate units, lateral projections on each of said grate units adapted to pass between one another, a grate frame for supporting said units, lateral extensions thereon and adapted to form part of the grate surface, vertical guide lugs thereon adapted to form guideways for the vertically movable grate units and depending lugs thereon adapted to form fulcrum points for the oscillating grate units and lever mechanism for operating the oscillating grate units and separate lever mechanism for operating and maintaining the vertically movable grate units in varying positions with respect to the oscillating grate units.

9. A coal burning grate comprising oscillating grate units and vertically movable grate units, lateral projections on each of said grate units adapted to pass between one another, a grate frame for supporting said units, lateral extensions thereon and adapted to form part of the grate surface, vertical guide lugs thereon adapted to form guideways for the vertically movable grate, the vertically movable grate units comprising a hollow body having a series of openings in the side walls thereof arranged one above the other, and projections on the end walls thereof adapted to fit within the vertical guide lugs on the grate supporting frame.

10. A coal burning grate comprising oscillating grate units and vertically movable grate units, projections on each of said grate sections adapted to pass between one another, a grate frame for supporting said units, vertical guides thereon adapted to guide the vertically movable grate units, depending lugs thereon forming fulcrum points for the oscillating grate units, the vertically movable grate units comprising hollow rectangular bodies having a series

of conical openings in the side walls thereof, arranged one above the other, and two separate lever mechanisms, one for the simultaneous control of all of the oscillating grate units and the other for the simultaneous control of all of the vertically moving grate sections.
